VACUUM CLEANER NOZZLE OR THE LIKE

Ralph A. W. Johanson, White Plains, N.Y., assignor to
Electrolux Corporation, Old Greenwich, Conn., a cor-
poration of Delaware

Filed Sept. 8, 1961, Ser. No. 66,659

Term of patent 14 years

(Cl. D9—2)

FIG. 1 is a top view of a vacuum cleaner nozzle em-
bodying my new design;

FIG. 2 is a front view of the nozzle shown in FIG. 1;

FIG. 3 is a bottom view thereof;

FIG. 4 is a rear view thereof; and

FIG. 5 is a perspective view showing the top and one
end of the nozzle shown in the preceding figures.

I claim:

The ornamental design for a vacuum cleaner nozzle or
the like, as shown.
